UNITED STATES PATENT OFFICE.

AUGUST LÜBBE, OF CAMBRIDGE, AND WILLIAM J. KEATING, OF BOSTON,
MASSACHUSETTS.

SLIDING-DOOR LOCK.

SPECIFICATION forming part of Letters Patent No. 535,915, dated March 19, 1895.

Application filed October 13, 1894. Serial No. 525,802. (No model.)

To all whom it may concern:

Be it known that we, AUGUST LÜBBE, residing at Cambridge, in the county of Middlesex, and WILLIAM J. KEATING, residing at Boston, 5 in the county of Suffolk, State of Massachusetts, citizens of the United States, have invented a new and useful Improvement in Locks for Sliding Doors, of which the following is a specification.

This invention relates to locks which are adapted to be placed upon sliding doors (often termed folding doors) for the purpose of locking them together; and it consists of a lock constructed somewhat on the Yale lock 15 principle, and in the manner hereinafter described, and illustrated in the accompanying drawings, in which—

Figure 1 represents a transverse vertical section of a portion of a couple of sliding doors 20 provided with our improved lock, which is shown in longitudinal vertical section in position therein. Fig. 2 is a transverse vertical section of the lock taken on line *y*, Fig. 1. Fig. 3 is an elevation of the "striker" or plate 25 on the door which is to receive the bolt. Fig. 4 is a horizontal section of the lock taken on line *x*, Fig. 2. Fig. 5 is a vertical section showing a modification.

Similar letters of reference indicate corresponding parts.

A and *A'* represent two sliding doors which are to be locked together. The door *A'* is provided with a suitable horizontal recess *B*, over the edge of which is screwed the striker 35 *C* provided with the opening *C'* having the extension or curved recess *C''* on one side of its edge, as shown in Fig. 3. The door *A* is provided with the lock, which comprises the main body or case *D* provided with, say, five 40 pin-chambers *E* occupied by the driving pins *e e'* operated by springs in the usual manner.

F is the cylinder provided with the pin holes *H* containing the pins *h* constructed as usual. *I* is the key. This cylinder has cut 45 upon its periphery a spiral groove *K* which makes one complete circuit of the cylinder. A screw *L* extends from the case *D* into said spiral groove. The cylinder is provided on its periphery next its inner end with an engaging pin *P*.

In operation, the key *I* is inserted and

turned, with the effect of rotating the cylinder. The screw *L*, by its engagement in the spiral groove *K* causes the cylinder, when it is rotated, to advance into the recess *B* in the door *A'*. As it thus rotatively advances, the engaging pin *P* passes spirally through the extension or recess *C''* in the edge of the hole *C'*. When the cylinder has sufficiently rotated, therefore, the driving pins *E* have 60 locked it by dropping into the pin-holds *H* in the ordinary manner, and the cylinder—which acts as a bolt—is locked in the recess by said pins and by the pin *P*, so that the doors *A A'* are firmly locked together. 65

The two outer driving pins *e'* do not act as locks when the cylinder has been turned into the door *A'*, and hence are provided with shoulders *e''* so that they will not drop as do the pins *e*, but can yield to the upward pressure of the corresponding pins in the cylinder as the key is inserted. Of course a reverse rotation of the cylinder withdraws it from the recess *B* in the door *A'*. 70

It will be observed that in the invention as above described the cylinder itself acts as a bolt and locks the doors together. In the modification shown in Fig. 5 the cylinder, when rotated, does not advance, being prevented from so doing by the pin *S* which lies in the groove *S'*; but a supplemental bolt *U* is provided which is furnished with a screw *U'* engaging a spiral groove *V* on the periphery of the cylinder. As the cylinder is rotated therefore, the bolt *U* is driven into the recess *W* in 85 the door by the engagement of the groove *V* with the screw *U'*.

Having thus fully described our invention, what we claim as new, and desire to secure by Letters Patent, is—

1. In a lock of the character described, the combination of the rotative cylinder *F* adapted to be operated by means of a key as *I* and provided with the pin holes *H*, pins *h'* and peripheral spiral groove *K*, the case *D* provided with the pin chambers *E* and driving pins *e e'* said driving pins *e'* being provided with shoulders *e''*, and the engaging screw *L* extending from the case into said groove, all arranged and constructed substantially as 100 and for the purpose set forth.
2. In a lock of the character described, in

combination, the cylinder F provided with the spiral groove K and pin P, the casing or body of the lock provided with the engaging screw L extending into said groove, and the striker C provided with the opening C' having the extension or recess C'', said striker being set over the edge of a recess in the door which is

to be locked to that provided with the lock itself, substantially as described.

AUGUST LÜBBE.
WILLIAM J. KEATING.
